CLAIM

I claim the ornamental design for a vehicle door for a storage area, as shown and described.

DESCRIPTION

FIG. 1 is a front perspective view of a vehicle door for a storage area showing my new design;

FIG. 2 is a rear perspective view thereof;

FIG. 3 is a bottom plan view thereof;

FIG. 4 is a front elevational view thereof;

FIG. 5 is a top plan view thereof;

FIG. 6 is a rear elevational view thereof;

FIG. 7 is a right side elevational view thereof; and,

FIG. 8 is a left side elevational view thereof.

The broken lines in the door body are unclaimed portions of the design.
